UNITED STATES PATENT OFFICE.

REINHOLD A. NORLING, OF AURORA, ILLINOIS, ASSIGNOR TO INDEPENDENT PNEUMATIC TOOL COMPANY, OF CHICAGO, ILLINOIS, A CORPORATION OF DELAWARE.

GRIP-HANDLE SWITCH FOR ELECTRIC DRILLS.

Application filed October 7, 1920. Serial No. 415,331.

To all whom it may concern:

Be it known that I, REINHOLD A. NORLING, a citizen of the United States, residing at Aurora, in the county of Kane and State 5 of Illinois, have invented new and useful Improvements in Grip-Handle Switches for Electric Drills, of which the following is a specification.

This invention relates to grip handle 10 switches for portable electric drills and like tools, and consists in the matters hereinafter described and more particularly pointed out in the appended claims.

In the accompanying drawings—

Fig. 1 is a longitudinal sectional view of 15 an electric drill provided with a grip handle and switch mechanism embodying the features of my invention;

Fig. 2 is an enlarged sectional view of the 20 handle, the switch mechanism associated therewith being shown in side elevation;

Fig. 3 is a transverse sectional view taken 25 through the handle on the indirect line 3—3 of Fig. 2;

Figs. 4 and 5 are side elevational views, 30 with parts in section, and showing the turret turned into "on" and "off" positions, respectively.

Fig. 6 is an enlarged longitudinal section- 35 al view taken through the turret;

Fig. 7 is a transverse sectional view taken 40 through the turret on line 7—7 of Fig. 6;

Fig. 8 is a sectional view taken through 45 one of the bearings for the turret on line 8—8 of Fig. 3; and

Fig. 9 is a sectional view of a detail of 50 construction and taken on line 9—9 of Fig. 5.

The electric drill or tool shown in the 55 drawings is of that type which may be readily picked up and be held in the hands of the operator while working with the tool and be easily carried or moved from one place of work to another.

The tool has an outside casing 1, in which 60 is located and housed the electric motor which turns the spindle of the tool. The motor has an armature shaft 2 extending lengthwise of the tool with its ends journaled in bearings in the drill casing 1. On the shaft 2 is an armature 3 and a commutator 4, the former rotating in a field or stator 5 retained in the drill casing, as usual in

electric drill construction of this general type. Electric current is supplied to the 55 motor through an outside cable 6 containing conductor wires 7 and 8. The cable enters the casing 1 at one side through a hole in the casing and is secured to the casing by a clamp 9. The portion of the cable entering the casing and immediately outside of the same is wrapped with a coil of wire 10 to protect such portion of the cable from injury and direct it away from the drill so as not to be unduly in the way. 60 65

Secured to the forward end of the casing 1 is a gear case 11, in which is journaled the drill spindle 12. This projects beyond the forward end of the gear case and is there provided with a chuck or tool holder 13, as 70 in drills of this kind. The spindle 12 is offset laterally from the armature shaft 2, as shown, and the latter drives the former through a suitable gear train, as illustrated.

At the rear or opposite end of the drill 75 case 1 is a handle 14, constructed in accordance with my invention. This handle has a hollow body portion 15, shaped and open at one end to fit over and receive the adjacent inner end of the drill case 1, as shown in 80 Fig. 1. The handle seats on a rib or shoulder 16 provided on the case 1, and the handle is detachably secured to the drill case by toggle bolts 17, 18, one carried by the handle and the other by the drill case, the bolts being received in outwardly opening slots provided in the respective parts. Nuts are applied on the bolts to clamp the handle and drill case together. The handle body 15 has a rearwardly extending neck portion 19 at 85 one side thereof, which joins the grip portion 20 of the handle with the body portion 15. This provides a passage-way between the free end of the grip portion 20 and the body portion 15, thus giving the handle an 90 open grip. 95

The switch mechanism of my invention 100 comprises a flat plate 21, as clearly shown in Fig. 3. This plate is secured by screws 22 to that end of the drill case 1 projecting into the hollow body portion 15 of the handle. The plate 21 is bifurcated at one side to provide two laterally spaced parts 105 23, to each of which is bolted a part 24 to provide split bearings for the rotary member or turret 25 of the switch mechanism, as

shown in Figs. 3 and 8. The turret 25 is made of fiber or other insulating material and is square in construction beyond said bearings. The portions of the turret in the 5 bearings are cylindrical so that the turret may be turned about its longitudinal axis. Secured to the turret between the bearings is a ratchet 26 provided with four teeth. The ratchet is made in two parts applied 10 about the turret in an annular groove and secured together and to the turret by rivets 27, as shown in Fig. 7. For turning the turret, there is a pawl 28 pivoted at 29 to a plunger 30 slidably mounted in a bore in 15 the neck portion 19 of the handle, as shown in Figs. 1 and 2. A flat spring 31 is rigidly secured at one end to the plunger 30 and has its other end bearing against the pawl 28 to normally hold the pawl in the operative 20 position shown in Fig. 1. The plunger 30 is slotted lengthwise to receive the pawl and its spring, and surrounding the plunger is a coiled spring 32 seating at one end on an annular shoulder in the bore and bearing 25 at its other end against a rib or shoulder on the plunger. In the construction shown, the plunger 30 is cylindrical, and to hold it against rotation and to limit its extent of sliding movement, there is a stop pin 33 in 30 the bore and fixed to the handle. This pin extends across an elongated slot 34 in said plunger. The ends of the slot when brought in contact with the pin limit the sliding movement of the plunger, and thus prevent 35 the plunger when moved inward from turning the turret more than a trifle over one-eighth of a turn, the ratchet teeth being arranged accordingly. The pin also limits the outward movement of the plunger by its 40 spring 32, and thus prevents the plunger from being ejected out of its bore.

On each side of the plate 21 is a pair of spring contact fingers, the fingers on one side of the plate being indicated by 35 and 45 the ones on the opposite side by 36, as shown in Fig. 3. The fingers are secured to the plate 21, and to accomplish this the plate has at each side an outwardly projecting flange or ear 37, on opposite sides of which 50 are blocks 38 of insulating material and against which the contact fingers are secured by bolts 39 in tubes 40 (Fig. 9) also of insulating material. The fingers have holes to allow the tubes to extend through them, and on the outside of each finger is a block 55 41 of insulating material and through which the tube and bolt extend, as shown in Fig. 9. Each pair of fingers 35, 36 have their free ends spanning the adjacent portion of the 60 turret 25 on the outside of the bearing thereof, and each finger carries a contact block 42 bearing against the portion of the turret therebetween, as shown in Figs. 4 and 5. Such portions of the turret are square in 65 cross-section and each has a hole bored

through across the axis of the turret to receive and hold a plug 43 made of brass or other material that will conduct an electric current. Each plug 43 extends clear through the turret and thus divides the end portion 70 of the turret at the plug into two diametrically opposed flat sections 44, 44, these being of insulating material. The contact blocks 42 are rounded, as shown, to enable the turret to be turned or rotated between them 75 for bringing either the plugs 43 or the insulated sections 44 into engagement with the blocks, as shown in Figs. 4 and 5, respectively. These parts are provided with shallow pockets or recesses 45, 46, respectively, 80 to receive the blocks 42 and hold the turret from turning accidentally.

A terminal plate 47 (Fig. 3) is in contact with one of the fingers 36 by being secured between the insulating blocks 38, 41 for that 85 finger, and said terminal is connected by a wire 48 with a terminal of the stator 5. Secured in like manner in contact with the other finger 36 is a terminal plate 49, to which is connected the supply wire 7, as 90 shown in Fig. 1. Secured in like manner to one of the fingers 35 is a terminal plate 50, to which is connected the other supply wire 8. A contact strip 51 is secured in like manner to the other finger 35 and leads to the 95 terminal of the brush holder 52, as shown in Fig. 2.

When the operator grasps the grip portion 20 of the handle, the natural position of his hand is with his thumb free to readily 100 reach and depress the plunger 30 without changing the position of his hand. To turn on the current to the tool, all that he is required to do is to depress or force the plunger 30 inward with his thumb. This causes the 105 pawl 28 to turn the turret 25 a trifle over an eighth of a turn. This brings the blocks 42 just over the corner of the square, and the tension of the contact fingers 35, 36 will act to complete the turning of the turret a full 110 quarter turn and cause the turret to snap into that position, with the blocks in contact with the plugs 43, and complete the circuit. The blocks will enter the shallow recesses in the plugs, as shown in Fig. 4. By 115 releasing the plunger 30, it will be returned to its starting position by its spring 32, and on the return, the pawl 28 will slip over the next tooth of the ratchet 25 to be in position to turn the turret again to cut off the current. When the plunger 30 is again depressed, the turret is turned in the same 120 manner and the blocks 42 brought into contact with the sections 44 of the turret, as shown in Fig. 5, and the current to the motor cut off. Thus, the current may be easily turned off and on by depressing the plunger sufficiently to cause the fingers to act on the 125 turret, as stated.

The natural position of the hand when 130

grasping the handle being with the thumb at the plunger 30, the switch mechanism may be operated to turn the current on and off without moving the hand along or off the handle or releasing the grip thereon.

After the plunger 30 has been depressed to turn on the current, the plunger can be moved back and forth to a considerable extent without in the least interfering with the contact of the switch because the plunger does not turn the turret a full quarter turn, the stop pin 33 preventing. The only way to interfere with the connection is to let the plunger back to its full stroke.

Both of the supply wires 7 and 8 lead to the contact fingers and, as the switch is so constructed that both leads are broken when the current is turned off, there is no chance left for short-circuiting as no current is present in the drill windings proper. This is a decided advantage because in connecting up a drill to the line there is no way of telling which one of the wires is the positive one and by having the switch break the current through both wires the advantage noted must necessarily follow.

The handle 14 having detachable connection with the drill casing 1 and the turret 25 and the contact fingers all being mounted on the drill casing, the handle may be removed from the drill casing without disturbing any of the connections between the switch mechanism and the supply wires and the contacts to the motor. These all being intact when the handle is removed makes it possible to run the drill with the brushes, commutator and all parts including the switch parts exposed for inspection.

The turret 25 is provided with integral flanges 53, 53, one inside of each bearing (23, 24) to hold the turret from shifting endwise.

The switch construction is positive in its action and substantial in its construction.

While I have shown and described herein in detail a handle and switch mechanism embodying the features of my invention, it is of course to be understood that the details of construction and arrangement of parts illustrated may be variously changed and modified without departing from the spirit and scope of my invention.

I claim as my invention:

1. The combination with an electric tool having a casing, of a handle having a hollow portion open to receive one end of the tool casing and secured thereto, and a switch mechanism, including a switch member in the hollow portion of said handle and rotatably mounted on said tool casing, a spring pressed plunger in said handle and depressible from the outside thereof, and a pawl and ratchet connection between said plunger and switch member to turn said member by depressing said plunger for

turning on and cutting off the current to the tool.

2. The combination with an electric tool having a casing, of a handle having a hollow portion open to receive one end of said tool casing and secured thereto, and a switch mechanism, comprising a turret of insulating material in the hollow portion of said handle and rotatably mounted on said tool casing, a spring pressed plunger in said handle and depressible from the outside thereof, a pawl and ratchet connection between the turret and said plunger to turn the turret by depressing the plunger, spring contact fingers bearing against said turret, and contact plugs in said turret and brought into and out of contact with said fingers as the turret is turned.

3. The combination with an electric tool having a casing, of a handle having a hollow portion open to receive one end of said tool casing and secured thereto, and a switch mechanism comprising a plate in the hollow portion of said handle and a turret of insulating material rotatably mounted on said plate, said turret having square portions, spring contact fingers mounted on said plate and bearing against said square portions on opposite sides thereof, contact plugs in said square portions and brought into and out of contact with said fingers as the turret is turned, and means including a ratchet on the turret and a depressible plunger on the handle for turning said turret.

4. The combination with an electric tool having a casing, of a handle having an open grip and a hollow portion open to receive one end of the tool casing, means detachably connecting said handle to said tool casing, and a rotary snap switch mechanism in the hollow portion of said handle and carried by said tool casing, and a spring pressed plunger in said handle and depressible from the outside thereof to operate said switch.

5. The combination with an electric tool having a casing, of a handle having an open grip and a hollow portion open to receive one end of said tool casing, toggle bolts detachably connecting said handle to said tool casing, and a rotary snap switch mechanism in the hollow portion of said handle and carried by said tool casing, and a spring pressed plunger in said handle and depressible from the outside thereof to operate said switch.

6. The combination with an electric tool having a casing, of a handle having a hollow portion open to receive one end of the tool casing and secured thereto, and a switch mechanism, comprising a turret in the hollow portion of said handle and rotatably mounted on said tool casing, a spring pressed plunger in said handle and depressible from the outside thereof, a pawl and ratchet connection between said turret and plunger to turn said

turn the turret less than a predetermined portion of a complete turn upon each depression of said plunger, and spring contact fingers bearing against said turret on opposite sides and acting to impart a quick snap movement to the turret to complete the turn.

7. The combination with an electric tool having a casing, of a handle having a hollow portion open to receive one end of said tool casing and secured thereto, and a switch mechanism, including a turret in the hollow portion of said handle and rotatably mounted on said tool casing, a spring pressed plunger in said handle and compressible from the outside thereof, a pawl and ratchet connection between said turret and plunger to turn the turret less than a quarter of a turn upon each depression of said plunger, and means independent of said plunger for imparting a quick snap movement to said turret to complete the quarter turn thereof and to turn the current to the tool on and off on the turning of said turret.

8. The combination with an electric tool having a casing, of a handle having a hollow portion open to receive the inner end of the tool casing and secured thereto, switch means for turning on and off the current to the tool, said switch means being located in the hollow portion of the handle between the latter and the tool casing and carried by one of the same, and means at the handle for operating said switch means.

9. The combination with an electric tool having a casing, of a handle having a hollow portion open to receive the inner end of the tool casing and secured thereto, switch means for turning on and off the current to the tool, said means being located in the hollow portion of the handle between the latter and the tool casing and being carried by one of the same, and means carried by the handle for operating said switch means.

10. The combination with an electric tool having a casing, of a handle having a hollow portion open to receive the inner end of the tool casing and secured thereto, a rotary snap switch for turning on and off the current to the tool, said switch being located in the hollow portion of the handle between the latter and the tool casing and carried by one of the same, and means carried by the handle for operating said switch.

11. The combination with an electric tool having a casing, of a handle having a hollow portion open to receive the inner end of the tool casing and secured thereto, a rotary snap switch for turning on and off the current to the tool, said switch being located in the hollow portion of the handle between the latter and said tool casing and carried by one of the same, a spring pressed plunger carried by said handle, and a pawl and

ratchet connection between said plunger and switch for operating the latter by said plunger.

12. The combination with an electric tool having a casing, of a handle having a hollow portion open to receive the inner end of the tool casing and secured thereto, a switch mechanism for turning on and off the current to the tool, said switch mechanism being located in the hollow portion of the handle between the latter and said tool casing and carried by one of the same, said switch mechanism comprising a turret of insulating material with square portions, contact plugs therein, spring contact fingers carrying rounded contact blocks brought into and out of contact with said plugs as the turret is turned, and means carried by said handle for turning said turret.

13. The combination with an electric tool having a casing, of a handle having a hollow portion open to receive the inner end of the tool casing and being detachably connected therewith, switch means for turning on and off the current to the tool, said switch means being located in the hollow portion of said handle and carried by said tool casing, all wires for supplying current to the tool through the switch means being carried by said tool casing so that the handle may be removed therefrom without disconnecting said wires, and means carried by said handle for operating said switch means.

14. The combination with an electric tool having a casing, of a handle having a hollow portion open to receive the inner end of said tool casing and being detachably connected therewith, a rotary snap switch for turning on and off the current to the tool, said switch being located in the hollow portion of the handle and carried by said tool casing, and means carried by the handle for operating said switch.

15. The combination with an electric tool having a casing, of a handle having a hollow portion open to receive the inner end of said tool casing and being secured thereto, switch means for turning on and off the current to the tool, said switch means being located in the hollow portion of said handle and carried by said tool casing, said handle having a hand grip and a neck portion, the latter connecting the grip with said hollow portion and means carried by said neck portion for operating said switch.

16. The combination with an electric tool having a casing, of a handle having a hollow portion open to receive the inner end of the tool casing and secured thereto, switch means for turning on and off the current to the tool, said switch means being located in the hollow portion of said handle between the latter and said tool casing and carried by one of the same, said handle having a grip and a neck portion, the latter connect-

ing the grip with said hollow portion, a spring pressed plunger slidably mounted in said neck portion and depressible from the outside thereof, and means in the hollow portion of the handle between the plunger and switch means for operating the latter by said plunger.

17. An electric switch mechanism, comprising a support, a plate secured thereto, a 10 turret of insulating material rotatably mounted on said plate and having square portions, contact plugs in said square portions and exposed on opposite sides thereof, spring fingers mounted on said plate and spanning said square portions of said turret, rounded contact blocks carried by said fingers and brought into and out of contact with said plugs as the turret is turned, a 15 ratchet carried by said turret, a spring pressed plunger adjacent said turret, a pawl carried by said plunger to turn said turret through the ratchet thereon, and a support for said plunger.

18. An electric switch mechanism, comprising a support, a plate secured thereto and having spaced bearings, a turret of insulating material extending between said bearings and journaled therein, a ratchet secured to said turret between said bearings, 25 said turret having square portions beyond said bearings, contact plugs in said square portions and exposed on opposite sides thereof, spring fingers spanning said square portions, rounded contact blocks carried by 30 said fingers and being brought into and out of contact with said plugs as the turret is turned, a spring pressed plunger adjacent said turret, a pawl carried by said plunger to turn said turret through the ratchet thereon, and a support for said plunger.

19. An electric switch mechanism, comprising a support, a plate secured thereto and having spaced bearings made in two parts clamped together, a turret of insulating material extending between said bearings and 45 journaled therein, a two part ratchet secured to said turret between said bearings, said turret having square portions beyond said bearings, contact plugs in said square portions and being exposed on opposite sides 50 thereof, ears on opposite sides of said plate, spring fingers secured at their inner ends to said ears and having their outer ends spanning said turret at the square portions thereof, rounded contact blocks carried by said 55 fingers on the inside thereof to be brought into and out of contact with said plugs as the turret is turned, a spring pressed plunger adjacent said turret, a pawl on said plunger to turn said turret through the 60 ratchet thereon, and a support for said plunger.

20. A switch mechanism comprising a rotary turret, a support therefor, said turret having square portions carrying contact 65 plugs exposed on opposite sides thereof, spring fingers on said support and spanning said turret at said plugs, rounded contact blocks carried by said fingers to be brought into and out of contact with said plugs in 70 turning said turret, the contact faces of said plugs and turret being wider than the blocks and having depressions therein to receive said blocks, means for turning said turret, and a support for said means. 75

In testimony that I claim the foregoing as my invention, I affix my signature, this 1st day of October, A. D. 1920.

REINHOLD A. NORLING.
